UNITED STATES PATENT OFFICE

2,003,414

EVAPORATOR FOR REFRIGERATING SYSTEMS

Edmund E. Allyne, Cleveland, Ohio

Original application December 24, 1931, Serial No. 583,061. Divided and this application September 30, 1933, Serial No. 691,716

3 Claims. (Cl. 62—99)

The invention disclosed in this application relates to refrigerating apparatus of the absorption type and is a divisional application of my pending application, Serial No. 583,061, filed December 24, 1931, now Patent 1,932,877.

One object of the invention is to provide an evaporator which is thoroughly heat insulated by a vacuum casing except for a small heat transfer portion which extends through the vacuum 10 casing and is connected to any suitable freezing unit structure, as for example, a brine tank having a socket for the exposed evaporator portion and a cube tray support in heat transfer relation with the brine tank.

15 A further object of the invention is to improve absorption refrigerating apparatus by providing the refrigerating compartment with a dome for receiving the evaporator and a freezing unit in limited heat transfer relation with the evaporator, 20 and a housing or casing enclosing the evaporator and freezing unit and provided with an adjustable thermostatic control means for regulating the circulation of air from the refrigerating compartment through the casing about the freezing unit 25 and dome, thereby controlling the temperature of the refrigerating compartment.

The foregoing and other features of the invention will be brought out in the following description, drawing, and claims.

30 Fig. 1 is a vertical section of the apparatus showing the refrigerator cabinet in cross-section.

Fig. 2 is a detail view disclosing the evaporator in cross-section.

In the embodiment shown in the drawing, the 35 cabinet comprises a front 1 having an upper refrigerating compartment opening and door 2 and a lower apparatus compartment opening and door 3. This front is connected to suitable side walls 4 of greater depth than the insulated refrigerating compartment, as will appear. These 40 side walls and front are mounted upon a suitable open base frame, generally indicated at 5. Mounted in the forward upper portion of the cabinet thus formed is the outer shell 6 of the refrigerating compartment which extends to the top of the cabinet and its bottom 7 is spaced from the lower frame 5 to provide an apparatus chamber or compartment 8. Mounted within and spaced from this outer shell 6 is an inner shell 9 with the 45 space between filled with suitable insulation 10. This inner shell has a ceiling 11, which is generally slightly higher than the top of the door and is provided with an upwardly extending heat collecting dome casing 12 normally in communication with the refrigerating chamber. This

dome casing has a suitable top 13 provided with a central longitudinal passageway or channel 14 for the circuit pipes which enter at the back and incline downwardly to the front from the rear. The top of the inner shell, the dome casing, and the top 13 are all encased in suitable insulation as at 15, a top layer 16 extending over the upper member of top 13. The refrigerating compartment being less in overall depth than the front to rear dimension of the cabinet leaves a rear vertical flue channel communicating with the apparatus compartment 8. This flue is utilized to carry away the heat from the still 22 and to contain some of the pieces of apparatus and connections and also house the water tank and main condenser. It is separated into two flues, 17 a main flue for receiving the rectifier, water tank, condenser and like parts, and the other an auxiliary flue for leading away the products of combustion from the still and also for housing the hairpin loop and trap. 10

A rectifier pipe branching into two interconnected legs, generally indicated at 31, extending through the partition into the flue 17 and there rising to a point near the top main flue and 25 passing horizontally to the opposite side where they are connected together in a single pipe 32 extending upwardly to a point near the top of the cabinet. Here the pipe extends forwardly and downwardly into a connection 33 leading to 30 the dome 34 of an evaporator 35 arranged in the heat dome. This evaporator has a relatively small downwardly extending heat transfer boss 36 which constitutes substantially the only heat transfer means between the evaporator and the 35 freezing unit.

In order to prevent the excessive absorption of heat from the box, the evaporator may be completely heat insulated, except for the boss 36 as by providing it with an additional shell or casing 35' spaced from it and providing a space from which the air may be exhausted, or the space may be filled with a heat insulating medium, the main point being to substantially insulate the evaporator from, and have it wholly 45 within, the refrigerating compartment.

The connection 33 is inclined downwardly toward the evaporator 35 and connected in its side to a condenser pipe leading down to a sump connected to the condenser. 50

The still is preferably encased in a suitable hood 41 having a stack portion leading to the auxiliary flue and with an opening 43 in the bottom of the hood to receive the burner and also to permit the passage of air upward around 55

the still. This hood or casing also protects the compartment 8 against excessive heat from the heating means.

The construction and arrangement of the still, flues, loop, rectifier, and hood form no part of the present application but are disclosed in detail and claimed in copending application 583,061, filed December 24, 1931, now Patent 1,932,877, of which this is a division.

10 In order to relieve the evaporator of any undue accumulation of absorbent or boiler liquor, a suitable drain is employed and it is connected by a gooseneck comprising the evaporator leg 48, Fig. 2, the upper member 49 leading out of 15 the main flue 17 into the auxiliary flue and there entering the bottom of a closed casing mounted upon the straight portion of the return bend of the hairpin loop communicating with the still. The top of this casing is connected by a 20 short small pipe with a downwardly extending larger pipe portion leading into the pipe at substantially the point slightly above but nevertheless at such a point with respect to the normal level of the boiler liquor at the end of the 25 refrigerating cycle that it will be sealed at the beginning of the heating cycle and thereafter be exposed during the refrigerating cycle.

Extending down into the box and co-extensive with the open mouth of the dome formed in the 30 top or ceiling of the refrigerating compartment is a freezing unit casing, generally of rectangular form and comprising sides 54 and a suitable back 55. At the front there is an inwardly extending margin or framework, generally indicated 35 at 56. This rectangular opening is for the reception of the ice trays, as will appear. The sides, back, and front extend out and are provided with flanges 57 engaging the under side of the top 11 of the refrigerating compartment. They are 40 held in place by suitable thumb screws 58. Near the top this casing is provided with suitable openings 59 for the passage of heated air from the top of the refrigerating compartment into the dome, and at the bottom it is provided with 45 an opening 60 adapted to be controlled by a damper 61 operated by a suitable thermostat. In this way the circulation of air through the freezing unit casing may be regulated.

Mounted in the casing 54 is a freezing unit

shell 71' provided with suitable cleats 71 for supporting cube trays 72. The top of this shell carries a brine tank 73 having a top 74 provided with a well or socket 75 adapted to fit the sump boss 38. This fit is somewhat loose and an efficient heat transfer medium between the cup on the one hand and the boss on the other is provided by water or mercury. In this way the direct heat transfer from the evaporator to the freezing unit is limited and is dependent upon the size of the boss and the cup. It has been found by experience that this is very effective for maintaining the box at the proper temperature and renders the temperature controllable by the simple regulation of the damper 61.

What I claim is:

1. In refrigerating apparatus, a cabinet, a heat insulated refrigerating chamber within said cabinet and having a heat dome extending upwardly from the ceiling thereof, an evaporator 20 in said cabinet and arranged in said dome, a heat insulated housing having an open front, means for removably securing said housing to the ceiling of the refrigerating chamber about the margin of said dome, and a removable freezing unit 25 in heat transfer relation with said evaporator and arranged in said housing.

2. In refrigerating apparatus, a cabinet, a heat insulated refrigerating chamber within said cabinet, and having its ceiling provided with an upwardly flared heat dome, an evaporator arranged in said chamber, a combined housing and freezing unit comprising a casing, a freezing unit comprising an ice tray frame, an upper brine tank mounted in said casing, and means for removably 35 securing said unit about the margin of said heat dome with the brine tank in heat transfer relation with said evaporator.

3. In refrigerating apparatus, a cabinet, a refrigerating compartment within said cabinet and having its top provided with an upwardly extended heat dome, an evaporator mounted in said dome, a freezing unit supported by said cabinet and including a brine tank in heat transfer relation with said evaporator, and an outer casing 45 secured to said cabinet and surrounding said freezing unit, said casing being provided with suitable draft openings.

EDMUND E. ALLYNE.
